COMBINED LATCH CASE AND ACTUATOR

Warner R. Lauper, San Pedro, Calif., assignor to Adams Rite Manufacturing Company, Glendale, Calif., a corporation of California

Filed Nov. 22, 1968, Ser. No. 14,591

Term of patent 3½ years

Int. Cl. D8—03

U.S. Cl. D8—109

FIG. 1.

FIG. 2.

FIG. 3.

FIG. 4.

FIG. 5.

FIG. 6.

FIG. 7.

FIG. 8.

FIG. 1 is a top plan view of a combined latch case and actuator showing my new design;

FIG. 2 is a bottom plan view of the same;

FIG. 3 is an elevational view taken from one side thereof;

FIG. 4 is an elevational view of one end thereof;

FIG. 5 is an elevational view of the opposite end thereof;

FIG. 6 is a longitudinal sectional view taken substantially on line 6—6 of FIG. 1;

FIG. 7 is a transverse sectional view taken substantially on line 7—7 of FIG. 1; and

FIG. 8 is another transverse sectional view taken substantially on line 8—8 of FIG. 1.

The dominant features of my design reside in the portions shown in full lines.

I claim:

The ornamental design for a combined latch case and actuator, as shown and described.
